UNITED STATES PATENT OFFICE.

EUGENE PEARL, OF NEW YORK, N. Y.

CRUTCH.

1,311,664.

Specification of Letters Patent. Patented July 29, 1919.

Application filed October 7, 1918. Serial No. 257,085.

To all whom it may concern:

Be it known that I, EUGENE PEARL, a citizen of the United States, residing at New York city, in the county of New York and State of New York, have invented new and useful Improvements in Crutches, of which the following is a specification.

This invention relates to improvements in implements for supporting the lame and assisting their locomotion, known generally as crutches.

The principal object of the invention is to produce a crutch in which the head or arm rest is engaged with the staff in such a manner as to be limitedly longitudinally movable relative thereto, cushioning elements being interposed in the joints therebetween to soften the effect of the constantly alternating pressure and relaxation of the parts when walking.

A further object is to produce a structure which can be shortened at any time, in an easy and convenient manner and without detrimentally effecting its operation or appearance.

These and other like objects are attained by the novel construction and combination of parts hereinafter described and shown in the accompanying drawings forming a material part of this disclosure, and in which—

Figure 1 is a side view of the upper part of a crutch made in accordance with the invention, parts being broken away to show the construction.

Fig. 2 is a top plan view of the same.

Fig. 3 is a side elevational view of the crutch head.

Fig. 4 is a fragmentary vertical sectional view taken through the center of the crutch head, the same showing the parts at the beginning of a forward step.

Fig. 5 is a side elevational view showing the parts as positioned at the termination of a step.

Fig. 6 is a perspective view of the connecting element used to unite the head and staff elements, and

Fig. 7 is a side elevational view of a complete crutch drawn to a reduced scale.

The head or arm rest of a crutch is most important, if of proper form, length, width and curvature, and highly polished with varnish or coated with celluloid, nearly all friction against the clothing is avoided—preventing wear of the same and the annoyance caused by under garments adjacent to

the arm pit heating and chafing, thereby eliminating much discomfort.

The arm piece, being entirely independent of the crutch uprights or staffs, adjusts itself to a considerable degree to the various positions of the crutch necessary in sustaining the body when walking, when the crutch is placed forward, the front spring receiving the principal weight, yields as the body is carried forward, the weight being transferred to the rear spring, which is then compressed. A cushion effect is the result—without causing the curved surface of the arm piece to change its form when supporting the body, which would be the result if the arm piece were padded or upholstered, a condition that has been found most impractical on account of its constant change of surface when in use and under pressure, causing clothing wear, friction, heating and chafing of the body.

A crutch to be comfortable, should not be too rigid, but so constructed that it will spring or yield to the various positions of the body, made necessary when walking. This improved construction permits the crutch parts to adapt themselves fully to the swaying of the body.

Referring now more particularly to the drawings, a pair of staffs or side members 10, having curved converging lower elements 11, connected by a band 12, extend down to a ferrule 14, connecting a resilient terminal or foot 15, preferably of rubber and adapted to make contact with the surface over which the user is passing in such manner as to partially cushion the step and to avoid slipping.

These staffs are firmly united by a band piece 17, at a point midway in their length, its exact location relative to the point of support being determined by the length of the arm of the user by means hereinafter described.

The main portions 10 and 11 of the staff may be oval, round, or of any preferred cross section, but the upper portions 18 are preferably cylindrical, like dowels, for several inches, as are also the combined bottoms adjacent to the ferrule 14, thus allowing the ends to be reduced in length so as to bring the hand grips 17 into proper position, enabling standard lengths of crutches to be carried in stock and adjusted when sold to meet requirements, by merely cutting the upper elements so as to bring the handle at a convenient distance from the head and

reducing the remaining excessive length by shortening the cylindrical part adjacent to the ferrule.

The head 20, is formed with a concave upper surface, reduced in width at the sides 21 and provided with horn-like extensions 22 and 23, respectively at the front and rear, so as to conform to the arm pit; this head is highly finished and preferably coated with celluloid as best adapted to resist perspiration and moisture, and to provide a smooth surface to contact with the garments.

The lower surface 24 is apertately recessed between a pair of bosses or extensions 25, each containing parallel cylindrically bored openings 26 suited to closely but slidably receive the upper ends 18 of the staffs, which are coated when entered, with a solid lubricant, as talc.

Spirally wound compression springs 28, suited to the weight of the user, are interposed between the bottoms of the openings 26, and the squarely cut ends of the staffs, as shown in Figs. 1 and 4, these springs providing a desirable cushioning effect and also permitting a swaying effect, as can be seen by comparing Figs. 4 and 5, the staffs being limitedly resilient in a lateral direction.

Secured to the lower concave surface 24 of the head is a metal strap 30, held firmly in position by screws 31, their extending ends 32 containing slots 33, through which pass other screws 34, engaging in the inner sides of the staffs, thus permitting a rocking movement to take place without relaxation or loosening of the parts, or the strap ends may be of thin resilient material always under tension against the staffs when pressure is applied causing various movements of the head.

From the foregoing it will be seen that a neat appearing and easily operating crutch has been disclosed, that can be used with entire comfort and safety, and due to the absence of loose parts, no squeaking, rattle, or other noise occurs when used.

Copies of this patent may be obtained for five cents each, by addressing the "Commissioner of Patents, Washington, D. C."

Having thus described my invention what I claim as new and desire to secure by Letters Patent, is—

1. A crutch comprised of a pair of support staffs spaced in their upper ends, a head recessed to slidably receive the ends of said staffs, compression springs in said recesses against which the upper ends of said staffs abut, an arcuately bent strap fixedly secured to the lower side of said head at its center, and means for securing the downwardly extending ends of said strap to the inner sides of said staffs, said securing means permitting a limited longitudinal movement of said staffs and maintaining said springs normally in an initially compressed condition.

2. A crutch comprised of a pair of support staffs spaced at their cylindrical upper ends, a head bored to slidably receive the ends of said staff, compression springs in said bored openings against which the upper ends of said staffs abut, a metallic strap suited to the bottom of said head, means for fastening said strap to said head, ends formed with said strap extending downward closely adjacent to said staff, slots in said ends, and screws passing through said slots into said straps holding said springs in compression and permitting a limited independent movement of said head relative to each of said staffs.

3. A crutch comprised of a pair of staffs, a head receptive of the tops of said staffs, compression elements in said head against which said tops bear, a U shaped metal strap with said head, and securing means set in said staffs, passing through slots formed in said strap whereby a rocking motion of said head on said staffs is permitted and also a limited relative movement therebetween.

In testimony whereof I have signed my name to this specification.

EUGENE PEARL.
